UNITED STATES PATENT OFFICE.

WARREN PARKER NEWELL AND CHARLES WALTER CARMAN, OF HAMBURG, IOWA.

BROOM.

1,222,237.

Specification of Letters Patent. Patented Apr. 10, 1917.

Application filed August 3, 1916. Serial No. 112,975.

To all whom it may concern:

Be it known that we, WARREN PARKER NEWELL and CHARLES W. CARMAN, citizens of the United States, residing at Hamburg, 5 in the county of Fremont and State of Iowa, have invented certain new and useful Improvements in Brooms; and we do declare the following to be a full, clear, and exact description of the invention, such as will enable others skilled in the art to which it 10 pertains to make and use the same.

This invention relates to new and useful improvements in brooms and more particularly brooms which are formed of a bundle 15 of suitable material surrounded by a band intermediate its ends pivotally mounted in a yoke, so that both ends of the material are adapted for use, and the primary object of the invention is to provide a suitable lock 20 which may be readily opened or closed to hold the broom in the yoke in either of its two positions.

Another object of this invention is to provide a yoke or carrier used in this broom 25 with a suitable lock, and to so construct the same that there will be no projections from the sides thereof to strike or mar furniture while the broom is in operation.

A further object of the invention is to provide a device of this character which is easily 30 and simply constructed, inexpensive to manufacture and one which will be very efficient in operation.

With these and numerous other objects in 35 view, our invention consists in the novel features of construction, combination and arrangement of parts which will be herein referred to and more particularly pointed out in the specification and claims.

40 Figure 1 is a side elevation of our improved broom;

Fig. 2 is an end elevation of the same;

Fig. 3 is a top plan view;

45 Fig. 4 is a vertical section taken on the line 4—4 of Fig. 1;

Fig. 5 is a perspective view showing the drum in open position and swung out of the frame;

50 Fig. 6 is a central vertical longitudinal section showing parts in elevation;

Fig. 7 is a horizontal section; and

Fig. 8 is a detail view showing the ar-

rangement of the slots in one of the sides of 55 the frame.

In describing our invention we shall refer to the drawings in which similar reference characters designate corresponding parts throughout the several views and in which 60 the numeral 1 designates the broom proper which consists of a suitably shaped bundle of straws or splints of equal length flat as shown clamped together centrally of their lengths by means of a strong band 2, and the 65 coarser ends of the bundle will be at one end 3, while the other end which is designated by the numeral 4 will comprise the finer ends of the bundle. The material from which the broom is made is placed in the center band 70 2 in such a manner that the same is arranged as follows. First an inner layer of asphalt or some similar glue, then a layer of straw or splints, is laid on, then an additional layer of glue, and so on until the band is entirely 75 filled. It has been discovered that the above method takes hold of each straw in the band, and will continue to hold the same firmly so that it cannot become loosened.

The means by which the broom proper is 80 carried comprises a yoke member 5, which consists of a U-bar 6 having upwardly projecting sides 7 that terminate at a central point in bent handle securing members 8, adapted to receive therein a handle 9. This 85 U-bar 6 has its opposite ends bent inwardly as shown at 10, and the said bar is disposed parallel with the band 2 that surrounds the broom when in position. The bent ends 10 of this bar are positioned a short distance 90 beyond the opposite ends of the band 2, and the same are connected therewith by connecting side portions or bars 11.

These side portions 11 are tubular flattened, as clearly shown in Fig. 7 of the 95 drawings. The side portions 11 will be made with spaces between the sides of the same and disposed in the spaces intermediate the ends, are wood fillers 12 for a purpose to be herein more fully described. These side portions 11 have their opposite ends fastened and the upper ends which are designated by the numeral 13 are riveted within the bent ends 10 of the U-bar, while the lower ends 14 are pivotally connected with the opposite 100 ends of the band 2 as shown at 15. The

space between the band 2 and the U-bar 6 is sufficient to hold therein one-half of the broom 1, so that when the same is positioned therebetween the other portion thereof will project downwardly and will be in an operative position.

The portion of the broom body that is disposed within the yoke is adapted to be locked therein by a cross arm 16 that is secured to 10 each of the side portions 11 of the yoke and which is adapted to swing across the opposite sides of said yoke to locked position as clearly shown in Fig. 1 of the drawings. The side portions are provided with a pair 15 of cross arms as will be obvious on each side of the yoke and for the sake of brevity we will specifically describe but one of these bars.

The cross bar comprises a pair of spring 20 wires 17, which are surrounded intermediate their ends and held together by a band 18, the said wires diverging outwardly from said band and having their extremities bent laterally and outwardly as shown at 19. 25 One of the side portions 11 adjacent the edge of the same is provided with a pair of spaced elongated openings therein, which are adapted to receive one end of the wires, and to pivotally engage the same so that the 30 cross arm is adapted to swing freely back and forth. The opposite side portion 11 of the yoke is provided with a pair of elongated slots 21, which are a shorter distance apart, than the normal space between the extremities 35 of the spring wires 17 of the cross bar, so that when it is desired to lock this arm in position, these arms are compressed and the bent extremities positioned in the slots 21 and released, whereupon they will expand 40 and will be securely locked therein. These cross arms 16 are positioned on opposite sides of the yoke adjacent the opposite edges of the side portions, so that when in operation they will be disposed beneath the plane 45 of the same and will not project therefrom to strike or mar furniture during the use of the broom.

In operation when the parts of the broom are disposed as shown in Fig. 1 of the drawing, the coarser ends 3 of the broom body will be disposed in the yoke while the finer ends 4 will be in operation. When it is desired to reverse this operation the detachable ends of the cross bars are contracted and withdrawn from the side portions 11, and they are swung outwardly out of the path of the front of the broom whereupon the broom may be revolved and the coarser end portion brought into operation while the finer end 55 will be positioned in the yoke. When the locking arms 16 are swung outwardly at right angles to their former position, they will rest upon the wood fillers 12 within the side portions 11 so there will be no chance of 60 their inner ends slipping into the space be-

tween the sides of the yoke. When swinging the locking cross arms back to position they may be easily locked and the broom body will be held stationary ready for operation.

The entire yoke and band may be surrounded by a cover C so as to absolutely overcome any chance of striking or marring the furniture by their hard surfaces during the use of the broom. This cover may be of any desirable material preferably some heavy fabric that is suitable for this use. This improved type of locking cross arms will be found very efficient and also they overcome the objections to carriers of this type inasmuch as they do not project from edges of the yoke. The method of securing the broom body in the band as has been hereinbefore described, will form sure gripping means for the same and will absolutely prevent slipping of the straws or splints.

From the foregoing description the construction and operation of our improved broom, the manner of applying the same to use and the operation thereof will be readily understood, and it will be seen that we have provided simple and efficient means for carrying out the objects of this invention.

We claim:

1. A device of the class described comprising a broom body of suitable material, a band surrounding the same intermediate its ends, a yoke having its sides pivotally connected with the ends of said band, a cross arm pivoted to each side and adapted to swing across the opposite edges of the yoke, said arms having expansible and contractible free ends adapted to be positioned in the opposite sides of the yoke.

2. A device of the class described comprising a broom body of suitable material, a band surrounding the same intermediate its ends, a yoke having its sides pivotally connected with the ends of said band, a cross arm including a pair of spring wires secured intermediate their ends and diverging outwardly therefrom, the extremities of one end of said wires being bent laterally and pivotally mounted in openings in the sides of the yoke, the opposite extremities of the wires having laterally outwardly bent extremities, and said ends adapted to be compressed and be positioned in elongated slots in the opposite sides of the yoke.

3. A device of the class described comprising a broom body of suitable material, a band surrounding the same intermediate its ends, a substantially U-shaped member having its head portion formed with upturned edges, handle securing means intermediate the ends of said head, substantially tubular flattened side bars for said member with laterally extending upper extremities secured in the ends of the head portion, said side bars having their lower ends pivotally con-

nected with the opposite ends of the band that surrounds the broom body, a locking cross bar pivoted in the diagonally opposite edges of the side bars, and a filler in each 5 side bar to hold the cross bars in operative position.

In testimony whereof we have hereunto

set our hands in the presence of two subscribing witnesses.

WARREN PARKER NEWELL.

CHARLES WALTER CARMAN.
